UNITED STATES PATENT OFFICE.

JOHN F. DUNN, OF NEW YORK, N. Y.

BUCKLE.

1,103,275.

Specification of Letters Patent. Patented July 14, 1914.

Application filed November 11, 1910. Serial No. 591,818.

To all whom it may concern:

Be it known that I, JOHN F. DUNN, a citizen of the United States, and a resident of the city of New York, borough of the Bronx, in the county and State of New York, have invented a new and Improved Buckle, of which the following is a full, clear, and exact description.

The object of the present invention is to form a buckle for belts the construction whereof is simplified and cheapened.

One embodiment of the present invention is disclosed in the structure illustrated in the accompanying drawings, in which like characters of reference denote corresponding parts in all the views, and in which—

Figure 1 is a perspective view of a belt having attached thereto a buckle constructed and arranged in accordance with the present invention; Fig. 2 is an edge view of the same; Fig. 3 is a longitudinal section taken on the line 3—3 in Fig. 4; Fig. 4 is a back view of a buckle constructed and arranged in accordance with the present invention; Fig. 5 is a cross section taken on the line 5—5 in Fig. 4; Fig. 6 is a detail view showing the sheet metal blank from which the body portion of the buckle is constructed; and Fig. 7 is a detail view showing the sheet metal blank from which is constructed the movable gripping member of the buckle.

In Fig. 6 of the drawings there is shown a sheet metal blank from which the body portion or face plate of the buckle is constructed. In Fig. 7 is shown the sheet metal blank from which the clamping member of the buckle is formed. The designating numerals applied to the features of construction in the buckle are likewise applied to the parts or sections of the blanks from which the said features are constructed. Thus, the face plate 11 is indicated in Fig. 6 by the same numeral as indicating the median longitudinal rectangular section of the blank. In the buckle adjacent to the face plate 11 and at either edge thereof are flanges 12, 12. The flanges 12, 12 serve as guides for the free end A of the belt B when the said free end is threaded through the buckle. Connected with the flanges 12 are overturned edge loops 13, 13 provided to form guide receptacles for the runners 14, 14 of the clamping plate.

The buckle is held to the belt B in fixed

relation thereto by a cross bar 15. In the present construction the cross bar 15 is formed in two sections, as seen in Fig. 6 of the drawings, being extensions of the flange 12 on each side of the body portion of the blank adapted to meet midway, as shown in said Fig. 6 in dotted lines.

At the receiving end of the buckle, where the free end A of the belt B is inserted in the buckle, there is provided a nosing or rolled ridge 16. The ridge 16 is extended from the inner side of the face plate 11, the object of the construction being to extend the face plate 11 from the body of the wearer to compensate at this end of the buckle for the added thicknesses of the belt under the opposite end of the said buckle. This arrangement produces the effect in the buckle when worn of leveling the same, or presenting an evenly curved surface concentric with the extension of the belt on both sides of the buckle.

When forming the body portion of the buckle from the blank shown in Fig. 6, the operations followed in order are:—The ends of the loop extensions 13 are overturned above the body of the loop extensions or the flanges 12, and disposed in parallel relation thereto, thus forming grooves opening each toward the other and parallel with the face plate 11. The nosing 16 is then formed by rolling the end sections 16 of the blank to form the ridge as seen in the drawings. The flanges 12 are then bent upward on the lines a—a, a—a in perpendicular relation to the face plate 11. At this stage in the proceedings in forming the buckle the clamp plate 17 is adjusted upon the body portion of the buckle. The clamp plate 17 is provided with the runners 14, 14 disposed at the outer edge of the body of the plate 17, and with finger extensions 18, 18 connected therewith. The extensions 18, 18 are protruded slightly beyond the flanges 12, 12 to afford a finger hold for the wearer of the buckle wherewith to adjust the clamp plate 17. The forward end or nose 19 of the clamping plate is upturned, as shown best in Fig. 3 of the drawings, to avoid the nose 16 of the body portion of the buckle. At the opposite end the clamping plate is depressed to form a gripping edge 20. The runners 14, 14 are inclined to form wedge members for the plate 17. The said runners and edge

20 are so arranged that as the clamping plate is forced toward the nosing 16 the edge 20 is forced toward the face plate 11. In the operation of the belt this action serves 5 to hold the belt between the edge 20 and the face of the plate 11, as the pull of the belt toward the nosing 16 serves only to move the edge 20 toward the inner surface of the face plate 11, thereby the more firmly gripping the belt interposed. The clamping plate 17 is placed in position upon the body portion prior to overturning the cross bar extensions 15, 15. When the cross bar extensions are so overturned they intercept 10 the clamp 17 to prevent the withdrawal of the same from under the loops 13, 13. With the formation of the cross bar 15 the buckle is structurally complete.

The construction in its simplicity and 20 openness of structure lends itself readily to any desired form of finish, such as plating, lacquering, or similar processes.

It is obvious that the clamping plate may 25 be shaped in proper dies, and at one operation, from metal cut to the form shown in the blank in Fig. 7, thereby reducing to a minimum the necessary manual labor in the construction of this part of the buckle. It is also evident that the body portion is quickly 30 and readily formed from metal cut to the shape of the blank in Fig. 6.

Having thus described my invention, what

I claim as new and desire to secure by Letters Patent is:—

In a buckle such as described, the combination with a movable clamp plate having laterally-disposed upturned cam-shaped runners; of a face plate constructed from sheet metal, having laterally-disposed upturned side flanges, said flanges being overturned 35 to form hook-shaped loops to receive and form a bearing for said runners, and said face plate having a cross bar for fastening a belt thereto, said cross bar being spaced apart from and constructed integral with 40 the body of the face plate and composed of two half sections extended from the raised edge of said flange toward the longitudinal median line of said face plate, to mutually receive the strain of said belt, and said face plate having on the end thereof opposite the said cross bar a curled portion to form a nosing, approximating in projection from the body of said face plate one half the space 45 between the said cross bar and body of the 50 face plate.

In testimony whereof I have signed this specification in the presence of two subscribing witnesses.

JOHN F. DUNN.
